US00D946074S

(12) **United States Design Patent** (10) Patent No.: **US D946,074 S**
(45) Date of Patent: **** Mar. 15, 2022**

(54) **CAMERA**

- (71) Applicant: **GoPro, Inc.**, San Mateo, CA (US)
- (72) Inventors: **John George Muhlenkamp, IV**,
Brisbane, CA (US); **Daniel J. Coster**,
San Francisco, CA (US); **Huy Phuong
Nguyen**, San Mateo, CA (US); **Kielan
C. Crow**, San Mateo, CA (US);
Nicholas Vitale, Foster City, CA (US)
- (73) Assignee: **GoPro, Inc.**, San Mateo, CA (US)
- (**) Term: **15 Years**
- (21) Appl. No.: **29/746,620**
- (22) Filed: **Aug. 14, 2020**
- (51) LOC (13) Cl. **16-01**
- (52) U.S. Cl. **USPC D16/218**
- (58) **Field of Classification Search**

(57) **CLAIM**

The ornamental design for a camera, as shown and
described.

DESCRIPTION

FIG. 1 is a top, front and right side perspective view of a
camera showing our new design;

FIG. 2 is a bottom, rear and left side perspective view
thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof; and,

FIG. 8 is a bottom plan view thereof.

1 Claim, 8 Drawing Sheets
